PAGE 3

Fig. 3.

Fig. 4.

Fig. 5.

Fig. 6.

The dominant features of my design reside in those portions thereof shown in full lines.

I claim:

The ornamental design for a household mixer, as shown and described.
